UNITED STATES PATENT OFFICE.

MELVIN H. LUCAS AND DENNIS B. KELLY, OF PORTLAND, OREGON.

COMBINATION PACKING-TOOL.

1,199,705.

Specification of Letters-Patent. Patented Sept. 26, 1916.

Application filed May 28, 1915. Serial No. 30,994.

To all whom it may concern:

Be it known that we, MELVIN H. LUCAS and DENNIS B. KELLY, citizens of the United States, residing at Portland, in the county of Multnomah and State of Oregon, have invented certain new and useful Improvements in Combination Packing Tools; and we do hereby declare the following to be a full, clear, and exact description of the 10 invention, such as will enable others skilled in the art to which it appertains to make and use the same.

This invention relates to new and useful improvements in combination packing tools 15 and the principal object of the invention is to provide a device which combines a packing tool with a remover.

Another object of the invention is to provide a packing remover which may be easily 20 and quickly operated by inserting the point thereof into the packing and swinging the point so as to form a hook which will engage the packing and permit the user to withdraw the packing by exerting pull on 25 the tool.

A further object of the invention is to provide a device of the above character to which may be secured tools of varying sizes and kinds which may be used in replacing 30 the packing.

Still another object of the invention is to provide a packing tool comprising a handle having a shank formed in one end thereof and pivotally mounted in the shank 35 is a trigger located near the handle and at the free end of the shank having a point pivoted which is connected to the trigger by a suitable connecting rod so that when the trigger is pulled the point will be swung 40 on its pivot to form a hook and engage packing to hold the same.

With these and other objects in view, the invention consists in the novel combination and arrangement of parts which will be 45 fully set forth in the following specification and accompanying drawings, in which:—

Figure 1 is a top plan view of a packing remover constructed in accordance with this invention. Fig. 2 is a side view partly in 50 section to more clearly illustrate the details of construction, and Fig. 3 is a sectional view of the forward end of the shank and the connecting rod showing the method of attaching the hook thereto.

55 Referring now to the drawings by charac-

ters of reference the numeral 1 designates the handle of the device while the numeral 2 designates the shank which tapers toward its free end and is preferably formed integral with the handle as illustrated.

Formed in the shank adjacent to the handle is a slot 3 and formed at the free terminal of the shank is the slot 4, these slots extending in parallel plane and transversely through the handle as shown.

Pivotaly mounted in the slot 2 on a suitable screw or rivet 5 is the shank 6 of the trigger designated generally by the numeral 7 which comprises the shank and the finger encircling ring 8 by means of which the 70 device is operated. The end of the shank 6 opposite the finger encircling ring 8 is pivotally connected in a bifurcation 9 formed in the rear end of the connecting bar 10 by means of a suitable screw or rivet 11. 75 The forward end of the connecting bar is preferably bifurcated as at 12 and adapted to receive a suitable screw 13 by which the point which will be more fully hereinafter described is pivotally connected to the connecting bar. 80

The point above referred to comprises the body 14 provided with the rearwardly extending ear 15 having formed therein an opening for the reception of the screw 13 85 and depending from the body 14 is an ear 16 which is pierced to receive the screw 17 which extends through the bifurcated portion 4 of the shank 2. Formed on the body 14 is a forwardly extending hook member 18 terminating in the point 19 which is arranged to engage in the packing so that the device may firmly grip the same to withdraw it from the stuffing box. It is to be understood that a number of these hook 90 members of varying sizes may be furnished with each of the tools so that where desired larger or smaller hook members may be used in larger or smaller openings. 95

Formed in the handle 1 is an axial internal screw threaded bore 20 for the reception of the threaded portion 21 of the shank 22 of the packing tool designated generally by the numeral 23 which comprises the shank 22 and the blade 24. It is to be understood that any desired number or forms of packing tools 23 may be substituted for the one herein described in order that the device may be made to be used under varying circumstances. 100 105 110

From the foregoing it will be apparent that in use the packing may be placed in a stuffing box in the usual way by inserting the proper tools in the handle 1 and when it is desired to remove the packing from a stuffing box the proper hook member is placed in the forward end of the shank 1 by removing the screw 17 and the ear 15 is then disposed in the bifurcated portion 12 of the connecting bar 10 and secured in place by the screw 13. It will thus be seen that when the trigger is in the position shown in Fig. 2 by the full line the point 19 may be inserted in the packing and upon pulling the trigger 7 into the position shown in the dotted line in Fig. 2, it will be apparent that the hook member will assume the dotted line position shown, and form a hook. Upon withdrawing a tool 20 from the packing box it will be apparent that the hook will pull the packing at the same time and thereby remove the same.

While in the foregoing there has been shown and described the preferred embodiment of this invention, it is to be understood that such changes may be made in the combination and arrangement of parts as

will fall within the spirit and scope of the appended claim.

What is claimed is:—

A combination packing tool including a handle, a shank on the handle, said shank being provided with a slot near the handle and being bifurcated at its free terminal, a trigger pivoted in the slot in the shank, a hook member comprising a body, an ear extending downwardly from the body and pivoted in the bifurcation in the shank, an ear extending rearwardly from the body, a connecting bar connecting the last mentioned ear with the trigger and being movable upon the upper face of the shank at a point formed on the forward end of the body to engage in the packing to enable the same to be removed when the device is in use.

In testimony whereof we affix our signatures in presence of two witnesses.

MELVIN H. LUCAS.
DENNIS B. KELLY.
